ROTARY SLIP

Lee O. Koen, Houston, Tex.

Original application December 2, 1935, Serial No. 52,546. Divided and this application January 9, 1939, Serial No. 249,915

6 Claims. (Cl. 24—263)

This invention relates to new and useful improvements in rotary slips.

With the increasing depth to which oil wells are drilled with rotary rigs, it has become necessary to increase the strength and size of the drilling apparatus. The increased length of the drill pipe or stem has added excessive weight and, therefore, the slips which hold the pipe in the rotary table have necessarily been changed.

10 In order to provide sufficient gripping surface to carry the load imposed by the length of pipe, the slips have been lengthened and manifestly, weight added.

Not only are these slips very heavy and difficult to handle, but owing to the increased load there is a greater tendency for the slips to wedge in the bushing. As the slips must be manually handled this condition makes the releasing of the slips much more difficult and the increased weight 15 not only adds to the burden of the workmen but slows down the operation, both in placing the slips and in releasing them, to the point where much time is lost.

One object of the invention is to provide improved means for hydraulically exerting an upward force against pipe slips, either for dislodging them from their seat and elevating or assisting in elevating them and holding them in an elevated position.

20 Another object of the invention is to provide improved hydraulically-operated auxiliary lifting or counter-balancing means connected with the slips so as to aid in lifting said slips and particularly to support them and, to a desired extent, 25 resist the lowering of said slips, whereby the load placed upon the workmen is reduced and the operation accelerated.

An important object of the invention is to provide an improved slip structure provided with 30 hydraulic actuating means for raising and lowering the slips, whereby a constant force may be exerted for lifting the slips and a steady and even cushioned lowering, is obtained.

35 A further object of the invention is to provide an improved slip assembly wherein either a liquid or a fluid may be used to actuate a reciprocating element for lifting and counter-balancing the slips, or wherein a liquid aided by mechanical means may be used to counter-balance the slips or aid in lifting the same. It is pointed out that the invention may be employed either to aid the workmen or to perform the raising and lowering of the slips and thus relieve the workmen entirely.

40 A construction designed to carry out the in-

vention will be hereinafter described, together with other features of the invention.

The invention will be more readily understood from a reading of the following specification and by reference to the accompanying drawings, in which an example of the invention is shown, and wherein:

Figure 1 is a plan view of a slip mechanism constructed in accordance with the invention,

Figure 2 is a view of the same, partly in elevation and partly in section, showing the slips lowered in pipe gripping position,

Figure 3 is a transverse, vertical sectional view showing the slips in elevated position,

Figure 4 is a similar view taken on the line 4—4 of Figure 2,

Figure 5 is a horizontal, cross-sectional view taken on the line 5—5 of Figure 2,

Figure 6 is a similar view taken on the line 6—6 of Figure 2,

Figure 7 is a transverse, vertical sectional view, similar to Figure 2, showing a modified form of lifting means,

Figure 8 is a partial, vertical sectional view of another form of lifting means.

This application is filed as a division of my co-pending application, Serial No. 52,546, filed December 2, 1935.

In the drawings, the numeral 10 designates an ordinary rotary table such as is commonly used with rotary well drilling rigs. Such tables have a central socket or opening 11 which is arranged to receive a flanged bushing 12. It is customary to construct the bushing in two sections so that the same may be removed when desired and replaced when the usual drill pipe or stem 13 is employed. A bowl 14, having an upwardly inclined or tapered bore 15, is mounted on top of the rotary table and has its reduced lower end 16 engaging within an enlarged annular recess 17 which surrounds the upper end of the bore of the bushing 12. A plurality of arcuate slips or slip members 18, having serrations or teeth 19 formed on their inner surfaces 20, are adapted to engage within the bore 15 of the bowl, where by the teeth 19 are caused to grip the pipe 13 when said slip members are lowered into said bowl as shown in Figure 2. Altogether six slip members are shown, it is to be understood that any number suitable for this purpose may be 35 used.

A dove-tailed groove 21 is disposed transversely within the outer surface 20 of each slip member so as to form an annular recess for receiving a pair of semi-circular or arcuate latch sectors or 40 45 50 55

segments 22 which are hinged together by a pin 23. Each sector is provided with an outwardly extending handle which has a hand grip 24 formed on its outer end. One handle 25 is made integral with one of the sectors, while the other handle 26 is hinged at 26' to the other sectors. The handle 25 is provided with a latch keeper 27, while the swinging handle 26 has a latch hook 28 arranged to engage the keeper when the handles are swung together, whereby the sectors 22 are fastened together around the slips and form a ring therefor.

The parts are so proportioned that when the sectors are latched together, the slip members 18 will be secured to the pipe 13 because of the "bite" or grip of the teeth 19 brought about by the pressure exerted in latching the sectors together. As shown in Figure 3, the sectors have a very loose fit in the grooves 21, whereby the slip members are free to undergo independent movement. Thus, the members are self-adjusting and may swing to a limited extent. In order to prevent creeping of the members on the sectors, a notch or recess 29 is provided in the upper edge of each member and are arranged to receive the heads of a plurality of machine screws 30 mounted in the sectors. These screws do not fit closely in the notches and, therefore, do not interfere with the swinging movement of the slip members.

A cylindrical housing or shell 31 surrounds the bowl 14 and is connected thereto by an annular top 32 and bottom 33, whereby an annular chamber or reservoir 34 is formed between said bowl 35 and housing. A hydraulic cylinder 35, having an external radial shoulder 36 intermediate its ends, is suspended within the reservoir 34 so that its open lower end is spaced a slight distance above the bottom 33 of said reservoir. The shoulder 36 is provided with a reduced screw-threaded lower portion which is arranged to engage within a screw-threaded opening 37 formed in the top 32 of the reservoir, whereby the cylinder 35 is mounted therein and projects above the surface 45 of the said top.

An elongate, cylindrical detent or plunger 28, having rounded ends, is disposed axially within the cylinder and is supported therein by having its rounded lower end engaging within the axial socket or recess of a piston 39 which has a snug sliding fit within said cylinder. An upwardly extending, outwardly curved hanger 40 is made integral with one of the latch sectors 22 at a point adjacent the cylinder 35. A lateral head 41, having a socket 42 formed in its underside is provided on the outer end of the hanger 40, whereby the head overhangs the upper end of the cylinder. The rounded upper end of the detent 38 projects through the upper end of the cylinder so as to engage within the socket 42 of the head 41 and may be secured to the latter by a suitable screw 43, whereby said detent is connected by the hanger 40 to one of the sectors 22. This arrangement provides a simple connection and permits a free rocking movement of the slip members.

The reservoir 34 is partially filled with a suitable fluid so as to provide a large air space or chamber thereabove. By introducing air under pressure into the reservoir by means of a valve 32' provided in the top 32, the liquid within said reservoir is forced upwardly into the cylinder 35, thereby elevating the piston 39 and rod 38 and in turn lifting the slips. It is noted that if the slips are latched on the drill stem or pipe 13, the same may be raised thereby and the hydraulic

lift used to sustain said slips in their elevated position. However, if the slips are not latched on said pipe, the same may be lifted by the hydraulic means. The air space in the reservoir is of such size that the upward and downward movement of the piston 39 within the cylinder 35 will cause only slight pressure changes as shown in Figure 3, the pressure actuated rod 38 will support the ring formed by the sectors 22 at a sufficient height to permit the slip members 18 to be 10 swung outwardly over the bowl 14.

When the device is being used, the slips are swung together and latched as shown in Figure 1. The hand grips 24 may be grasped by a workman so as to swing the handles 25 and 26 together. When the hook 28 has engaged the keeper 27, the teeth 19 of the slip members will grip the surface of the pipe 13. This gripping action is accentuated by the sliding and wedging contact between the flat adjacent faces of the hook 20 and keeper. Since the slip members are latched on the pipe, it is obvious that the same will be carried downwardly with said pipe when the latter is lowered, whereby the inclined outer surfaces 20 of said members will engage within the 25 bore 15 of the bowl 14. This forcing of the slips into the bowl assures a proper and safe anchorage of the pipe. When the slip members are moved downwardly the valve 32' is opened so as to exhaust the compressed air, whereby the rod 30 38 and piston will slide downwardly within the cylinder 35.

When it is desired to release the slips, the pipe is raised in the usual manner to lift the slip members from the position shown in Figure 2 to the 35 position shown in Figure 3. In this manner, the slips will be forcibly pulled out of the bore 15 of the bowl 14. However, the liquid within the reservoir 34 may be compressed, as hereinbefore set forth, to force the piston 39 and rod 38 upwardly, whereby the compressed liquid assists in lifting the slips to their upper position. It is pointed out that the principal function of the compressed liquid is to support the rod and piston in an elevated position, whereby the slips will be 43 supported. When the slips have been moved to their upper position, the handle 26 may be swung manually to disengage the latch and then both handles may be swung so as to swing the slip members away from the pipe.

It is noted that the pressure actuated rod and piston may be utilized to assist in elevating the slips. If the teeth 19 of the slip members retain their grip on the pipe, the slips will be elevated when said pipe is raised. However, if the slips should lose their grip on the pipe and start to slide downward thereon when the latter is raised, the pressure-actuated rod and piston will raise or assist in the manual raising of the slips.

In Figure 7, a modified form of the invention 60 is shown and includes the usual rotary table 10' and flanged bushing 12'. An elongate, vertical well or chamber 43 is provided in the rotary table and extends upwardly through the flange of the bushing and a cylindrical boss 44 which projects 65 above the top of the bushing. The well or chamber provides a smooth cylindrical bore for receiving an elongate piston or plunger 45, which has a sliding fit therein. A flexible packing cup 46 is secured to the lower end of the plunger, 70 while a cap 47 is mounted upon the upper end of said plunger.

A yoke 48, having a hollow block 49 pivoted therein, is carried by the cap 47. A cylindrical trunnion 50 engages within the block 49 and has 75

sliding fit therein. A split lifting ring 51 engages within an annular recess formed by transverse grooves 52 which are disposed in the external surfaces 20' of the slip members 18' adjacent and 5 below the grooves 21. The ring is composed of a pair of complementary sections which are formed with overlapping ears 53. The trunnion 50 is provided on its inner end with a reduced eye 54 which engages between the ears 53 and is 10 secured thereto by a pin 55, whereby the ring 51 is hinged to the trunnion. The lifting ring has a loose fit in the slip members so as not to interfere with their swinging movement. It will be observed that the pin 23 of the latch ring overlies 15 the hinge pin 55 of the lifting ring, whereby the slip sections which are defined by the sectors may be freely swung open when the device is unlatched.

A vertical duct 56, extending down through 20 the rotary table 10', is provided with a lateral extension 57 which communicates with the bottom of the well 43. A hydraulic cylinder 58 is mounted on the table and has a piston 59 slidably disposed therein. A short pipe 60 connects 25 the forward portion of the cylinder to the upper end of the duct 56. A suitable liquid such as oil, is placed in the cylinder and fills the ducts 56 and 57 and the well 43 below the plunger 45. The piston 59 is provided with a piston rod 61 30 which extends through an adjustable head 62 screw-threaded into the rear end of the cylinder. A coiled spring 63 surrounds the rod 61 and is confined between the head 62 and the piston 59.

35 With the slips lowered into the bushing 12' and the plunger in its lower position as shown, the liquid within the well 43 is forced into the cylinder 58 and the piston 59 displaced, whereby the spring 63 is compressed. By adjusting 40 the head 62, the degree to which the spring is compressed may be varied so as to obtain the desired slip balance. When the slip members 18' are lifted to their upper position, the compressed spring forces the liquid from the cylinder 45 through the ducts in the well 43, thereby tending to lift the plunger 45 in much the same manner as the compressed liquid in the hereinbefore described form.

In Figure 8, another hydraulic form is shown 50 wherein the slips 64 are formed of two semi-circular sectors or sections, hinged together in the usual way. The bushing 65 has a reservoir or chamber 66 and an inclined bowl 67 conforming to the slips. Each slip sector has a handle 55 68 loosely connected thereto and provided with a rigid depending piston 69, slidably confined within a cylinder 70 which extends down into the reservoir 66. The cylinders and pistons have the same inclination as the bowl 67 and 60 when said pistons are actuated, similarly to the piston 39 of the first form, they will raise and lower the slip sectors.

In this form, the slips will become disengaged from or release the pipe after the initial upward 65 movement of the same. The handles 68 may be detachably connected to the pistons 69 so as to permit removal of the slips without removing the pistons. It is pointed out that this device will serve mainly as a counter-balancing means 70 to decrease the amount of manual labor. When no latching means is employed, it is obvious that the pipe will not move the slips, except perhaps

during its initial upward movement unless the handles 68 are manipulated so as to grip said slips on said pipe. If this is not done, the slips will be raised and lowered only by the hydraulic means and will be, of course, counter-balanced, 5 in any position, by controlling said hydraulic means.

While the slips have been shown with teeth 19 for gripping the pipe, it is to be understood that 10 said slips may be provided with any suitable means for gripping the pipe, so long as they retain their hold on said pipe and are moved thereby when brought into gripping position on the same. It is manifest that the latching means may be entirely eliminated or used in 15 any suitable form. It has been found expedient to illustrate means for manually opening and closing the slips, but any suitable means may be employed for this purpose.

Various changes, alterations and modifications 20 may be made in the size, shape and arrangement of the herein described elements, within the scope of the appended claims.

What I claim and desire to secure by Letters 25 Patent is:

1. A pipe slip, including a slip bowl, a hydraulic plunger mounted uprightly on the bowl, a plurality of pipe slips, a hinged supporting member engaging around the slips and provided with a releasable latching means, said support- 30 ing means being connected to said plunger.

2. A pipe slip including, a slip bowl, a hydraulic plunger mounted upright on the bowl, a plurality of pipe slips, a pair of hinged supporting members carrying said slips and provided with 35 a releasable latching means, said member being supported by said plunger, and said plunger being of sufficient length to raise the bottom of said slips above said bowl.

3. A pipe slip including, a slip bowl, a hydraulic plunger mounted uprightly on the bowl, a plurality of pipe slips, a pair of hinged supporting members carrying said slips and provided with a releasable latching means, said member being supported by said plunger, and 45 said plunger being of sufficient length to raise the bottom of said slips above said bowl so that said slips when raised above said bowl may be manually swung laterally.

4. A pipe slip including, a slip bowl, a hydraulic plunger mounted uprightly on the bowl, a plurality of slips, a slip supporting member engaging around the slips, said member being supported by said plunger, and said plunger being of sufficient length to raise the bottom of said slips above said bowl. 50

5. A pipe slip including, a slip bowl, a hydraulic plunger mounted uprightly on the bowl, a plurality of slips, a slip supporting member engaging around the slips, said member being supported by said plunger, and said plunger being of sufficient length to raise the bottom of said slips above said bowl so that said slips when raised above said bowl may be manually 55 swung laterally.

6. A pipe slip device including, a slip bowl, a hydraulic plunger disposed uprightly on the bowl, and pipe supporting elements carried by and movable with the plunger, said plunger being of such length as to move the slips entirely 70 out of the bowl.

LEE O. KOEN.
